TOY WEAVING MACHINE

Gerald M. Rodmaker and Jacob M. Burkart, Cincinnati,
Ohio, assignors to Kenner Products Company, Cincinnati,
Ohio, a corporation of Delaware

Filed Nov. 21, 1968, Ser. No. 14,565

Term of patent 14 years

Int. Cl. D21—02

U.S. Cl. D34—15

FIG. 1

FIG. 2

FIG. 5

Fig. 4

Fig. 5

FIG. 6

FIG. 7

FIG. 1 is a perspective view of the toy weaving machine showing our new design;

FIGURE 2 is a side elevational view from one side thereof;

FIGURE 3 is a side elevational view from the other side thereof;

FIGURE 4 is a front view thereof;

FIGURE 5 is a rear view thereof;

FIGURE 6 is a top plan view thereof; and

FIGURE 7 is a bottom plan view thereof.

We claim:

The ornamental design for a toy weaving machine, substantially as shown.
